ELLIOTT FISHER COMPANY, OF NEW YORK, N. Y., A CORPORATION OF DELAWARE

TYPEWRITING MACHINE

Application filed March 12, 1928. Serial No. 260,844.

This invention pertains to typewriting machines, and more particularly to a means for mounting portable models on a baseboard forming part of a carrying case.

Portable typewriters are constructed as low as possible. The feet of the typewriter are made low, and extend but slightly below the frame. The shallow recesses, on account of small wall area, have very little holding power, and have proven unsuitable, because it has been found that, in carrying the typewriter from place to place, the edges of said recesses have become chipped or otherwise damaged, and cease to properly function. A purpose of this invention is to overcome the present failings, and to furnish additional advantages. To accomplish this, hanger-plates are fastened on top of the baseboard above the recesses.

After affixing said plates, the typewriter is placed in position on the baseboard, and the feet or supports pass through holes in the plates and extend into said recesses, which are oversize, so that the typewriter, when being carried about, hangs upon the hanger-plates.

The addition of said hanger-plates does not increase the height of the typewriter above the baseboard, because the thickness of the plates lies within a clearance space between the frame of each typewriter and the bottom surface of its feet, which (when the machine is in normal working position) rest upon the floors of the oversize recesses.

When the baseboard with the typewriter thereon is in a vertical or carrying position, the weight of the machine is primarily carried by its feet, which usually are of rubber. The weight upon said feet is carried by the hanger-plates, such weight being distributed through the lower surface of the plates to the baseboard. The weight of the typewriter is distributed, when hanging or carried vertically, to eight points on the baseboard. A result of such wide distribution of weight is a lessened strain at each of the points on the baseboard where such weight is transmitted. This again results in a more enduring baseboard, if kept at its customary thickness, or permits the use of a thinner baseboard, still

able to withstand the dead weight. Said hanger-plates also afford some measure of reinforcement against exterior blows on the baseboard when the latter forms part of a carrying case.

Other features and advantages will hereinafter appear.

In the accompanying drawings,

Figure 1 is a partial vertical transverse section of a portable typewriter with a baseboard.

Figure 2 is a partial vertical longitudinal section of a portable typewriter with a baseboard, along the line 2-2 of the baseboard, Figure 3.

Figure 3 is a plan view of a baseboard, showing hanger-plates mounted thereon over recesses, and having the typewriter removed.

Figure 4 is an isometric view of a hanger-plate, with its set screw.

In carrying out this invention, I provide a baseboard 10, having in its upper surface a plurality of recesses 11 into which extend resilient feet 12, fastened by screws to a typewriter-frame 13. Metallic reinforcing bushings 14 are preferably mounted in the baseboard 10, and internally threaded to receive set screws 15 or anchoring screws 16.

Secured to the baseboard 10 by the set screws 15 are the two hanger-plates 17, in the positions shown by Figure 3. These plates 17 form two units, each one performing the same functions respectively for two feet or supports, on each side frame of the typewriter. Each hanger-plate is of elongated shape, and includes a pair of annular portions 23 having foot-size openings 24, the recesses 11 being oversize, so that, when the hangers 17 are in position on the baseboard, the edges of the openings 24 just overlie the edges of the oversize recesses 11, and thereby sustain the weight of the machine when being carried about. The recesses 11 are made oversize, to allow for slight alterations in the size of the baseboard from the usual causes.

Forwardly-extending brackets 18 are secured respectively to flanges, near the front of and on each side portion of the typewriter-frame, as best shown in Figure 1, said brackets being held to the frame by rivets or

screws 19. Extending downwardly through the brackets 18 and through openings 25 in the plates 17 are anchoring stud screws 16, having coil springs 20 disposed between their heads 21 and said brackets. When the hanger-plates are in position on the baseboard, the anchoring screw-holes in the bushings 14 register with the small end holes 25 of each plate 17. As these holes 25 are of smaller diameter than the shanks of anchoring screws 16, only the threaded portion of the latter can be passed through. When this has been done, they are screwed into threaded underlying bushings set into the baseboard. This not only holds down the typewriter-frame, but also anchors the ends of said plates 17, and co-operates with screws 15 extending through openings 26 and threaded into bushings 14 to rigidly hold said plates to the baseboard. Other anchoring means 22 at the rear of the machine co-operates with the front anchoring means to retain the typewriter-frame 13. As the clearance between the typewriter-frame and the baseboard should be maintained at a minimum, and as there is a projecting screw-head 28 below the bottom of each side frame of the typewriter, a clearance hole 27 is cut in each plate 17, into which said screw-head can project.

30 Variations may be resorted to within the scope of the invention, and portions of the improvements may be used without others.

Having thus described my invention, I claim:

35 1. Means for fastening a typewriter frame having feet to a baseboard, comprising, a hanger plate having its parts in a single plane, said hanger plate having a perforation near each end through which the feet may be inserted and withdrawn perpendicular to said plate, means for fastening the plate to said baseboard, said means passing through the base board and typewriter frame for preventing the frame from moving perpendicularly from the base board.

40 2. Means for fastening a typewriter frame having feet to a baseboard, comprising, a hanger plate having its parts in a single plane, said hanger plate having a perforation near each end through which the feet may be inserted and withdrawn perpendicular to said plate, said board having sockets opposite said perforations into which said feet may extend, means for fastening the plate to said baseboard, said means passing through the base board and typewriter frame for preventing the frame from moving perpendicularly from the base board.

45 3. Means for attaching a typewriter frame having feet to a baseboard, comprising, a hanger plate extending in a single plane, said hanger plate having perforations to receive the feet of the typewriter frame, and the baseboard having sockets opposite said perforations into which the feet may extend, perfor-

rated bushings extending through the baseboard and means passing into the bushing through the hanger plate to hold the hanger plate and frame from moving perpendicularly from said board.

70 WILLIAM A. DOBSON.
